UNITED STATES PATENT OFFICE.

MARTHA L. ZIDELL, OF LOS ANGELES, CALIFORNIA, ASSIGNOR TO PATSY FROK & ROMPER CO., OF LOS ANGELES, CALIFORNIA, A CORPORATION OF CALIFORNIA.

DESIGN FOR A CHILD'S GARMENT.

57,294.

Specification for Design.

Patented Mar. 8, 1921.

Application filed February 11, 1920. Serial No. 357,816. Term of patent 14 years.

To all whom it may concern:

Be it known that I, MARTHA L. ZIDELL, a citizen of the United States, residing at Los Angeles, in the county of Los Angeles and State of California, have invented a new, original, and ornamental Design for a Child's Garment, of which the following is a specification, reference being had to the accompanying drawing, forming part thereof.

Figure 1 is a front view of a child's garment showing my new design, and

Fig. 2 is a rear view thereof.

The essential feature of my design consists in providing a child's garment of the character indicated in the drawing, an upper or waist portion having a skirt-like section diverging outwardly from immediately or shortly below the arms and terminating in a

broad arc giving the effect of a sweeping curve and producing sharp angular flares projecting on either side of the garment.

Otherwise than as above indicated the remaining appearance, outline, construction or ornamentation of a garment to which my design has been applied is immaterial as to my design.

I claim:

The ornamental design for a child's garment substantially as described and shown.

Signed at Los Angeles, California, this 3d day of February, 1920.
